UNITED STATES PATENT OFFICE.

ELIJAH BROOKES, OF STOKE-ON-TRENT, ENGLAND.

DIE FOR FORMING HANDLES FOR CUPS, ETC.

1,417,967.

Specification of Letters Patent. Patented May 30, 1922.

Application filed June 15, 1916. Serial No. 103,860.

(GRANTED UNDER THE PROVISIONS OF THE ACT OF MARCH 3, 1921, 41 STAT. L., 1313.)

To all whom it may concern:

Be it known that I, ELIJAH BROOKES, subject of the King of Great Britain and Ireland, and resident of Hanley, Stoke-on-Trent, in the county of Stafford, England, earthenware manufacturer, have invented 5 certain new and useful Dies for Forming Handles for Cups, Etc., of which the following is a specification.

10 My invention relates to a new or improved die press to be employed in the manufacture or formation of handles for tea cups, breakfast cups, jugs and the like articles of pottery, the object being to produce handles 15 more perfect in shape and with their ends cut at the right position and angle to fit the contour of the body or vessel to which they are to be applied.

Prior to the date of this invention the 20 handles have usually been pressed out of plastic clay, then placed on a board to dry. When the handle is in a suitable condition 25 the ends thereof are cut to a cutting mark which is very seldom in the correct position owing to the handle having been deformed or bent in the process of making and drying. In the majority of cases the cutting mark on 30 the handle is out of place, consequently when cut to the cutting mark the handle does not fit the contour of the body or vessel and when forced against it springs away in drying. Or if a deformed handle obtains a good hold 35 of the body or vessel it will often pull it out of shape when drying and firing.

My invention will be fully described with 40 reference to the accompanying drawings in which:—

Fig. 1 is a side elevation of a die press constructed in accordance with my invention,

Fig. 2 is a front elevation of same,

Fig. 3 is a similar view to Fig. 1 showing a slight modification to be hereinafter described,

Figs. 4 and 5 are front and side elevations, 45 respectively, of the die in its closed position,

Fig. 6 plan of the lower part of the die and

Fig. 7 a plan illustrating a hand tool for cutting the ends of the handles to be herein- 50 after described.

My invention is designed with the object of overcoming the disadvantages hereinbefore referred to and consists in the employment of a device in the form of a die press A

constructed to retain the correct shape of the 55 handle during the cutting of its ends and to sever the ends at the right position and angle to fit the body of the article. The said press A has a die b formed in two parts b¹ b², each part being recessed at c to correspond with 60 the shape of the handle which the die b has to accommodate. The die may be constructed of metal or other suitable material. The lower part b¹ of the die is fixed to a block or 65 plate d carried by a pillar e on a base or frame f. Secured to the lower die block are guide rods g the upper ends of which are supported by a fixed crosshead or plate h. The upper part of the die is constructed to 70 slide on the guide rods g in and out of contact with the lower fixed part b¹ of the die. The die can be removed from the press by unscrewing the set screws b³ and other dies 75 substituted as desired. The die block j is normally held up in its highest position, as shown at Figs. 1 to 3, by a spring k the upper end of which is connected to a pillar l fixed on the crosshead h whilst its lower end is connected to a rod or projection m secured to the upper die block j. n is a spring on the 80 rod m for cushioning the upper die block j when it is pulled up by the spring k.

Figs. 1 and 2 show the press carried by a vertical pillar e the two parts of the die being in a horizontal position, but to facilitate 85 the easy insertion and withdrawal of the handles from the die I prefer to slightly incline the press as shown at Fig. 3.

The front face x of the die, through which the ends o o¹ of the handle slightly project 90 (see Fig. 6), is shaped to the contour of the article to which the handle has to be applied, and a cutting tool of corresponding shape is passed along the face of the die to cut off 95 and shape the ends of the handle to fit the contour of the vessel. A very convenient hand tool p is shown at Fig. 7 the blade q being shaped to correspond with the face x of the die. When the tool blade is passing along the face x of the die the ends o o¹ of 100 the handle are severed thereby. By shaping the ends o o¹ of the handle to fit in the manner described it is not necessary to force the handle to the vessel and consequently there are no sprung handles. By raising the 105 spring controlled pin r (Fig. 2) which passes through a hole s in the bottom part of the die b¹ and into the handle recess c the fin-

ished handle may be dislodged or raised out of the recess and be easily removed.

Any other approved cutting or scraping devices, besides the blade q , may be used for 5 trimming the ends of the handles.

What I claim as my invention and desire to secure by Letters Patent is:—

1. A die press for use in the manufacture or formation of handles for articles of pottery, consisting of a frame, a die formed in two parts, the upper part being slidable on 10 guide rods and spring controlled, handle recesses formed in the die and extending to the front face thereof, said die being curved or shaped to enable the ends of the handle to 15 be cut at the right angle or shape, and a spring controlled pin for dislodging or raising the finished handle, substantially as described.

20 2. In a press for use in the manufacture or formation of handles for articles of pot-

tery, the combination, with the die having recesses to accommodate the handle, of a cutting tool or knife shaped to correspond with the front face of the die and to sever the ends 25 of the handle, substantially as described.

3. A die press for handles, comprising a frame provided with guides, and a pair of die blocks one of which is slidable in the 30 said guides, the said die blocks having handle-shaped recesses formed in their adjacent faces and extending to their front faces, and having their front faces shaped so that the projecting ends of the handle can be suitably trimmed off to fit the vessel to which they 35 are to be attached.

In testimony whereof I have hereunto set my hand in the presence of two witnesses.

ELIJAH BROOKES.

Witnesses:

PATTIE PLANT,
I. BENTON.
